Inventor

UNITED STATES PATENT OFFICE.

WILSON T. ROBERTS, OF COLUMBUS GROVE, OHIO.

CARPET-CLEANING MACHINE.

1,231,940.

Specification of Letters Patent.

Patented July 3, 1917.

Application filed September 27, 1916. Serial No. 122,421.

To all whom it may concern:

Be it known that I, WILSON T. ROBERTS, a citizen of the United States, residing at Columbus Grove, in the county of Putnam, 5 State of Ohio, have invented a new and useful Carpet-Cleaning Machine; and I do hereby declare the following to be a full, clear, and exact description of the invention, such as will enable others skilled in the art 10 to which it appertains to make and use the same.

This invention relates to an improved carpet cleaning machine, and an object of the invention is to provide an efficient and 15 practical machine of this kind, in which improved features of construction are involved.

A further object of the invention is to provide a wire fabric cylinder having an 20 elongated opening at its bottom, so that a carpet to be cleaned may be moved about the cylinder, so that as the carpet passes the opening, the carpet may be automatically beaten to remove the dust and dirt.

25 A further object of the invention is to provide means for carrying the carpet about the wire fabric cylinder, in combination with a mechanism for rotating said means.

30 A further object of the invention is the provision of means actuated by said mechanism for beating the carpet as it moves past the elongated opening along the bottom of the wire fabric cylinder.

A further object of the invention is to 35 provide means actuated by said mechanism for fanning the dust downwardly through the opening, that is, to impart a blast of wind against the inner face of the carpet as it passes the opening, so that the dust will 40 be forced down.

A further object of the invention is to provide means to hold the carpet adjacent the cylinder and prevent the same from binding.

45 In practical fields, the details of construction may necessitate alterations falling within the scope of what is claimed.

The invention comprises further features and combination of parts, as hereinafter set 50 forth, shown in the drawings, and claimed.

In the drawings:—

Figure 1 is a view in side elevation of the carpet cleaning machine, showing parts broken away, to more clearly disclose some 55 of the details of construction.

Fig. 2 is a longitudinal sectional view.

Fig. 3 is a transverse sectional view on line 3—3 of Fig. 1.

Fig. 4 is a transverse sectional view on line 4—4 of Fig. 1.

Fig. 5 is an end view of the carpet cleaning machine, showing the gear connections between the carpet beating means, the fanning means and the means for rotating the chains, which carry the carpet about the 65 wire fabric cylinder.

Fig. 6 is a detail view of a portion of one of the chains, showing the carpet clamping means.

Fig. 7 is a detail sectional view of a part 70 of one of the chains and through the clamp.

Referring more especially to the drawings, 1 designates a base frame, which may be any suitable shape, preferably rectangular, consisting of the longitudinal side and 75 end pieces 2 and 3, and the central piece 4, and fixed to the top of the base frame is a piece of wire fabric 5. Rising upwardly from the opposite ends of the base frame are the end walls 6 and 7 of the carpet cylinder 80 80. This cylinder 8 consists of a plurality of metallic bands 9, which are provided with annular channels 10. However, the bands 9 are not completely circular, by reason of the fact that their corresponding 85 lower portions are cut away, and the opposite ends of each band, where the cutaway portion occurs, terminate a trifle inwardly from the longitudinal sides of the base frame. The opposite end bands 9 are provided 90 with ears 11, through which suitable screws or the like 12 pass, in order to secure the end bands to the end pieces 6 and 7 of the carpet cylinder. These bands 9 are connected by intermediate wire fabric pieces 95 13, which correspond in length to the bands 9. Since the bands 9 have their lower portions cut away, and the wire fabric pieces 13 corresponding thereto, it is to be noted that the carpet cylinder is provided with a 110 longitudinal opening 14 at the bottom. The end pieces 6 and 7 of the carpet cylinder are connected by the longitudinal strips or bars 15, which are spaced in accordance with the width of the opening 14, and to the lower 105 edges of which strips or bars 15 the opposite ends of the bands 9 and the wire fabric pieces 13 are secured by screws or the like 16, thereby rendering the parts more secure and rigid. An arched sheet metal cover 110 17 is secured to the edges of the end pieces 6 and 7, to cover the carpet, not shown, as

it travels or moves about the cylinder, there being a longitudinal strip 18 extending along the top of the cover 17, and secured in any suitable manner to the upper edges 5 of the end pieces 6 and 7. Connected to the lower edges of the arched cover by means of suitable hinged connections 19 are closures 20, which may be opened, when fitting a carpet upon the cylinder, or when 10 removing a carpet. Extending about the bands 9 and moving in the channels are suitable chains 21. At corresponding points on said chains clamps 22 are pivoted, as at 23. Each clamp consists of the two plates 15 24 and 25, which have arms 26 mounted upon the pivot 23. The arms of the plate 25 fit between the arms of the plate 24. The plate 24 has an integral screw 27 extending through an opening 28 of the plate 20 25, and is provided with a winged nut 29 for drawing the two plates toward each other, to clamp one edge portion of a carpet or rug between them, as shown in Figs. 6 and 7, there being spurs 30 carried by the 25 plate 24, to pierce the carpet and extend through the plate 25 to insure holding the carpet between the two clamping plates. Secured by rivets or the like 31 to the upper inner face of a cover 17 are spring arms 30 32, to the corresponding ends of which a rod 33 is connected in any suitable manner. This rod 33 bears upon the carpet, and holds the same closely against the fabric cylinder. Mounted in bearings of the end 35 pieces 6 and 7 are the shafts 34 and 35, which are provided with sprocket wheels 36, with which the carpet carrying chains engage, so that when the shaft 34 is rotated, the chains 21 will move in the channels 10 40 of the bands 9. Mounted in bearings of the end pieces 6 and 7 are the pintles 37 and 38 of the rotating shaft 39 which is rectangular in cross section. This rotating shaft 39 is provided with eyes 40 upon its several 45 faces. Connected from one eye to another on each face for the entire length of the shaft is a carpet beating chain 41. Each carpet beating chain 41 is so connected to the eyes, so as to form loops, and the loops 50 of one chain are in staggered relation to the loops of an adjacent chain, so as to insure beating all parts of the carpet as it passes the longitudinal opening. The pintle 38 of the shaft 39 is provided with a gear 42 55 and a sprocket wheel 43, about which a sprocket chain 44 (which may be operated from any suitable source of power, not shown) travels, so as to impart revoluble movement to the shaft 39. A stub shaft 45 60 is carried by the end piece 7, and has a gear 46 thereon. Also mounted in bearings of the end pieces 6 and 7 is a shaft 47 provided with radial arms 48, to which the fan blades 49 are connected in any suitable manner. One end of the shaft 47 has a gear 50,

which meshes with the gear 46, so that when the shaft 39 is rotated, the shaft 47 will correspondingly rotate. In this case, the fan blades will generate a volume of air, which tends to percolate through the carpet as it 70 passes the opening 14, to insure forcing the dust and the like downwardly, so as to remain below the wire fabric piece or strip 5, that is, as the carpet beating chains are constantly striking the carpet. A second 75 stub shaft 51 is carried by the end piece 7, and is provided with a gear 52, which meshes with a gear 53, which is also carried by the stub shaft 45. On one end of the shaft 34 a gear 54 is keyed, and which gear 80 54 meshes with the gear 52, so that when the gear 46 (which, together with the gear 53, are carried by a sleeve 55) rotates, the gear 52 is correspondingly rotated through the medium of the gear 53, thereby imparting motion to the shaft 34, which in turn through the sprockets 36 of the shaft 34, will rotate or move the chains through the channels 10, and being that the carpet is clamped to the chain, the carpet will be 85 moved about the cylinder in order to be beaten. The end pieces 6 and 7 are provided with openings 56, to permit air to enter the cylinder. Air through the openings 56 may be regulated by manipulating or 90 opening the closures 57, which are pivoted upon the pins 58.

The invention having been set forth, what is claimed as new and useful, is:—

1. In a carpet cleaning machine, the combination of a casing and a wire fabric cylinder mounted therein having annular channels, of means movable in the channels to carry a carpet about the cylinder, said cylinder having an opening in its bottom over which the carpet passes, and a revoluble member rotatable adjacent the opening and provided with beaters to strike the carpet as it passes over the opening. 100

2. In a carpet cleaning machine, the combination of a casing and a wire fabric cylinder mounted therein having an opening at its bottom, of a wire fabric covered compartment below the opening, said cylinder having channels, chains movable in the 105 channels and having clamps, by which the carpet may be connected to the chains so as to move about the cylinder and across the opening, and a carpet beater adjacent the opening, to beat the dirt downwardly from 110 the carpet and into said compartment. 115

3. In a carpet cleaning machine, a substantially cylindrical casing having a base with an elongated opening therein, a wire fabric cylinder in said casing and having 120 its wall spaced from the casing, whereby a carpet may pass between the cylinder and the casing, means rotating around the cylinder and provided with devices whereby said carpet may be connected to said means, 125 130

shafts mounted in bearings of the ends of the casing and provided with gears engaging said means for rotating the same, said cylinder having an opening in its lower wall 5 and provided with longitudinally extending strips on the interior of the cylinder, one on each side of said opening of the cylinder, a revoluble shaft journaled in said casing between the strips and provided with 10 beaters to strike the carpet as it passes over the opening of the cylinder, means for stirring the air in the cylinder and casing, and causing the air to percolate through the carpet as it passes said openings to force the dirt downwardly, means at the ends of the 15 casing to permit air to enter the casing, and means for imparting movement to the carpet carrying means, the carpet beating means and the means for stirring the air.

In testimony whereof I have signed my 20 name to this specification in the presence of two subscribing witnesses.
